UNITED STATES PATENT OFFICE

DEWEY H. BITNEY, OF ALBION, MICHIGAN, ASSIGNOR TO UNION STEEL PRODUCTS COMPANY, OF ALBION, MICHIGAN

REENFORCE CHAIR

Application filed January 31, 1931. Serial No. 512,550.

The main object of this invention is to provide an individual reenforce chair element which is very stable, even when embodied in elements of considerable height.

5 Objects pertaining to details and economies of my invention will definitely appear from the description to follow. The invention is defined in the claim.

A structure which embodies the features 10 of my invention is clearly illustrated in the accompanying drawing, in which:

Fig. 1 is an elevation of my improved reenforce chair looking from the left of Fig. 2.

Fig. 2 is a side view of my reenforce chair.

15 Fig. 3 is a fragmentary view illustrating a plurality of my reenforce chairs in operative relation to a form and to the reenforce bars supported thereby.

In the accompanying drawing 1 represents 20 a form and 2 represents reenforce bars. My improved reenforce chair comprises a U-shaped seat member 3 adapted to receive a bar, as 2, and having downwardly diverging legs 4 terminating in U-shaped extensions 5.

25 The lower arms 6 of these U-shaped extensions 5 are disposed horizontally and at right angles to the legs constituting feet. These arms 6 extend at each side of the vertical plane of the pair of legs 4 so that the structure 30 is stable, even when embodied in supports of considerable height commonly known as reenforce high-chairs.

35 My improved reenforce chair may be produced very economically and is strong and stable.

Having thus described my invention what I claim as new and desire to secure by Letters Patent is:

40 A reenforce chair comprising a U-shaped seat member having its arms extended into downwardly diverging legs, the seat member, arms and legs occupying substantially the same vertical plane, said legs terminating in similarly facing U-shaped extensions, the 45 bottom arms of said extensions being disposed

horizontally at right angles to the legs constituting feet and projecting at each side of the vertical plane of the legs.

In witness whereof I have hereunto set my hand.

DEWEY H. BITNEY.
